FREDERICK J. GUBELMAN, OF ENGLEWOOD, NEW JERSEY, ASSIGNOR TO THE REGINA COMPANY, OF NEW YORK, N. Y., A CORPORATION OF NEW JERSEY.

DIAPHRAGM FOR TALKING-MACHINE SOUND-BOXES.

1,279,104.

Specification of Letters Patent. Patented Sept. 17, 1918.

Application filed July 7, 1917. Serial No. 179,174.

To all whom it may concern:

Be it known that I, FREDERICK J. GUBELMAN, a citizen of the United States, residing at Englewood, Bergen county, State of New Jersey, have invented certain new and useful Improvements in Diaphragms for Talking-Machine Sound-Boxes, of which the following is a specification.

My invention relates to a diaphragm for 10 a talking machine sound box and has for its object to provide a diaphragm which shall have improved acoustic properties.

More particularly, it is the object of my invention to provide a diaphragm which 15 shall reproduce vocal, musical and other tones of whatever pitch or character without chattering, blasting or other unpleasant sound effects and in accurate correspondence with the sound impulses which are to be 20 reproduced.

Another object of my invention is to provide a diaphragm for the purpose described which can be definitely standardized as to dimensions and other physical characteristics and which shall, withal, be simple and economical to construct and easily assembled into operative relations with its associated parts.

My invention will be better understood by 30 referring to the accompanying drawings in which Figure 1 represents a central longitudinal section through a sound box containing a preferred form of diaphragm according to my invention; Fig. 2 is a view similar to Fig. 1 showing a modification of my invention, certain parts common to the two figures being omitted; Fig. 3 is a view similar to Figs. 1 and 2 showing still another modification of the invention; Fig. 4 represents 40 the diaphragm of Fig. 3 before it has been mounted in the sound box and before its parts have been clamped together in operative position, and Fig. 5 is a plan view looking from below of Fig. 3.

Referring to the drawings, 1 is the sound 45 box casing having the usual tube 2 for connection to the tone arm and a circular recess or chamber 3 to receive the diaphragm 4 which is preferably a flat mica disk of suitable thickness; any suitable material usual in the art may, however, be employed instead of mica.

In the form of the invention shown in 55 Fig. 1 the recess 3 is provided with a peripheral outwardly convexed shoulder 5

against which the disk 4 is forced by a clamp ring 6 which has threaded engagement with threads 7 formed on the inner wall of casing 1. This results in a convexing of and a consequent stretching and stiffening of the 60 disk.

A screw 8 fastens the center of the disk to one end of an operating lever 9 whose outer end is twisted and bent so as to be attached to the rim of the casing 1. A thinned region 10 provides a fulcrum about which the lever 9 can oscillate. This operating lever 9 itself supports at 11 one arm of a bell crank lever 12 which is arranged to rock about an axis transverse to said arm and mounted upon the casing 1, thus actuating the stylus 13 which is held by the other arm of the bell crank lever in correspondence with the movements of the diaphragm.

In operation it will be found that the diaphragm is sensitive to a greater degree and more accurately responsive to vibratory impulses to which it may be subjected than is the case with diaphragm of the usual type when simply held or supported at their 80 edges without internal stiffening or stretching as just described.

It is believed that the improved results produced by my novel diaphragm are due to the same reasons which cause superior 85 results to be produced by a well stretched drum head over that produced by a loosely stretched drum head.

In the form of the invention shown in Fig. 2 the shoulder at the bottom of recess 90 3 is square to the axis of the recess, but the mica disk is clamped against it between an inner rubber ring or washer 14 and an outer rubber ring 15 of substantially larger diameter. The result is to force the outer periphery of the disk inwardly and to bow or convex the disk 4 outwardly as in the form of Fig. 1. The diaphragm 4 is similarly stretched and stiffened.

The diaphragm in the form of my invention shown in Figs. 3, 4 and 5 has clamped to it upon its rear side a comparatively small diametered concave disk of aluminum 16 of about the same thickness. The screw 8 in this case passes through both aluminum 100 and mica disk and has its end threaded into one end of the operating lever 9 as before. In this form of the invention, however, the screw 8 is intended not merely to hold the parts together, but also to produce the re- 110

quisite bowing, stiffening and stretching of the diaphragm. It should, hence, be set or drawn up sufficiently to bring about a con-caving or cupping of the mica disk within 5 the area covered by the aluminum disk. This results in a consequent stretching and stiffening of the entire disk which is, therefore, made more sensitive and more accurately responsive to vibratory impulses to 10 which it may be subjected. The aluminum cup is also greatly stretched and stiffened. The two disks should not, however, be so tightly clamped as to bring them in contact except over a narrow annulus near the outer 15 margin of the smaller disk.

The diaphragm is preferably held in the recess 3 by a clamp ring 6 of the usual character which engages the interior threads 7 and presses the diaphragm against a soft 20 rubber ring 17 which rests upon the bottom of the box. A rubber washer 18 is pref-

erably placed between the clamp ring and the diaphragm.

I find that "chattering" and "blasting" is completely eliminated in sound boxes hav- 25 ing diaphragms as above described.

Variations of detail may be made by those skilled in the art within the spirit and scope of the following claim:

In a sound box, the combination of a cas- 30 ing, a diaphragm held in said casing, a stylus arranged to rock with respect to said casing and a lever operatively connected be- 35 tween stylus and diaphragm, said dia- phragm comprising a plate of larger di- meter and a central cup with periphery in contact with the plate and its center drawn forcibly toward the plate thereby dishing the plate and flattening the cup.

In testimony whereof, I have hereunto set 40 my hand.

FREDERICK J. GUBELMAN.
